UNITED STATES PATENT OFFICE.

NEWTON SELBY WILSON, OF MERIDIAN, ASSIGNOR TO DANIEL GILDMACHER,
OF COLUSA, CALIFORNIA.

DESIGN FOR A HAME-HOOK.

SPECIFICATION forming part of Design No. 24,041, dated February 12, 1895.

Application filed December 27, 1894. Serial No. 533,126. Term of patent 14 years.

To all whom it may concern:

Be it known that I, NEWTON SELBY WILSON, a citizen of the United States, residing at Meridian, in the county of Sutter and State of California, have invented and produced a new and original Design for Hame-Hooks, of which the following is a specification, reference being had to the accompanying drawing, in which the figure is a perspective view of my hame-hook.

The leading feature of my design is a hame hook having a cruciform slot formed in it between its ends, with the arms of the slot extending transversely and its leg longitudinally of the hook, said hook having its outer end curved on the same side of the body as that to which the hook end is turned, and into which curved outer end the extremity of the leg of the slot extends and terminates.

A is the hame hook, the general shape of

which is oblong. At one end it has the hook *a* of the usual form. Its other or outer end *a'* is curved to the same side as the hook end *a*. In the body of the hook is the cruciform slot *a²*. The head of this slot lies well up toward the hook end, the arms lying transversely of the device, while the leg lies longitudinally thereof and its extremity or foot extends to and terminates within the curved end *a'*. Thus the whole cruciform slot is contained within and inclosed by the hame hook.

What I claim is—

The design for a hame hook herein shown and described.

In witness whereof I have hereunto set my hand.

NEWTON SELBY WILSON.
